F. FUREDY

PENCIL

Filed July 22, 1924

Inventor

FRANK FUREDY

By his Attorney

J. Granville Meigs

UNITED STATES PATENT OFFICE.

FRANK PUREDY, OF NEW YORK, N. Y., ASSIGNOR TO BUSWICK NATIONAL BANK.

PENCIL.

Application filed July 22, 1924. Serial No. 727,489.

My invention relates to pencils in which provision is made for adjustment and ready interchange of leads.

The general object of the invention is to provide means for easily and quickly selecting and placing in active position any one of a plurality of leads or crayons. In some cases one of the marking elements may be a stylus point, but in that case it will be arranged and manipulated substantially as in the case of leads or crayons, and such stylus rods or points will therefore not be further mentioned.

Another object is to provide a convenient arrangement for a plurality of leads which differ from each other in color or other characteristics, with a lead selector, and an indicator for the selector, by which the character of the selected lead can readily be ascertained.

A more particular object is to provide in convenient and economical form an improved lead carrier and selector, with improved means for guiding the selected lead to and from active position and for gripping or retaining it adjustably in active or projected position.

A further object is to provide means for realizing the above stated objects in a structure of attractive and symmetrical form, and in which there is no necessity for any outward or visible eccentric or other unsymmetrical portion, such as an eccentric or offset point or tip portion.

A further object is to provide simple and easily manipulated devices for selecting and adjustably securing the desired lead.

The characteristics and advantages of the invention are further sufficiently described in connection with the following detail description of the accompanying drawings, which show certain exemplifying embodiments of the invention. After considering these embodiments, persons skilled in the art will understand that many variations may be made, and I contemplate the employment of any structures that are properly within the scope of the appended claims.

Fig. 1 is a longitudinal section of a pencil embodying the invention in one form.

Fig. 2 is a transverse section at 2—2, Fig. 1.

Fig. 3 is a section at 3—3, Fig. 1.

Fig. 4 is a section at 4—4, Fig. 1.

Fig. 5 is a perspective view of the main

magazine, or rotatable element of the selector, separated from other parts.

Fig. 6 is an elevation of the complete pencil.

Fig. 7 is a section at 7—7, Fig. 1.

Fig. 8 is a section at 8—8, Fig. 1.

The body of the pencil is a tubular structure, and while in some cases a single tube or casing may be employed, in some preferred cases, as here shown, the casing may consist of an upper tube 1 and a lower tube 2, these parts having a screw connection 3. In the lower casing section a cylindrical guide piece 4 is placed with a close or press fit, so that it will not become accidentally displaced, or if necessary it may be secured positively in any suitable way. In the guide piece is formed a longitudinal passage or guide channel 5 which is preferably arranged at a slight angle to the axis of the casing, so that its lower end is centered at the axis and its upper end is eccentric or is located at a point near one side of the casing. The mouth 6 of the guide channel is desirably flared so that the lower edge of the channel opening is practically flush with the inner surface of tube 2.

A lead grip is located at the lower end of the casing, and while the construction of this grip may vary considerably, in a preferred example it is constituted as follows: The lower end of tube 2 has its thickness increased as at 7, by swaging or in any other suitable way, and in this thickened portion is screwed a nipple 8, the lower part of which is formed into longitudinally-divided spring grip or clutch fingers 9. A clamping sleeve or tip 10 is screwed on the outward part of nipple 8, and the outward portion of this tip is tapered, and the inner surface 11 of the tapered portion co-operates with the grip fingers 9 to clamp them upon the lead which is in active position. The lower inner portion of tube 2 is formed with a surface 12 leading to the nipple bore and arranged to properly guide leads into it.

A combined magazine and selector is provided, which is located in the upper part of the casing, that is, substantially within the tube 1. This may be conveniently identified as the main or "active" magazine so far as its lead holding and separating function is concerned, since it is provided to hold and separate the leads intended for active use, in distinction from another or auxiliary

magazine or container for spare leads, referred to hereafter. The active magazine comprises a head 15 and the magazine proper, or spacer, 16. The head includes an outer cylindrical portion 17 and an inner cylindrical portion 18, usually of small diameter and dimensioned to be located with a bearing fit within the upper end of tube 1. The magazine or spacer 16 is desirably 10 formed of sheet metal and while it may consist of separate strips angularly arranged, preferably it is formed by folding a single wide strip of thin sheet metal to the form clearly shown in Fig. 5 and in the cross 15 sections, Figs. 2 and 3. The spacer thus consists of four equal spaced blades or partition walls 19 meeting at the center, which is at the axis of the casing. Each pair of blades or walls 19 form, in conjunction with 20 the adjacent casing wall, a pocket or compartment 20, in which one of the active leads, such as 21, is placed. In some cases the lower end of the magazine or spacer may be close to or rest upon the upper end 25 of guide cylinder 4; but preferably a short cylindrical plug 25 is interposed at this point.

The plug 25 is preferably arranged so that about one-half of it fits within the upper end 30 of tube 2 and the other portion is contained within the lower end of tube 1 when the two tubes are screwed together as clearly shown in Fig. 1. At one side of the plug is an aperture 26 registering with the lower end 35 of the guide bore or channel 5 in guide piece 4. The spacer has a close or push fit in the upper end of tube 1 so that it can be readily removed and replaced when the tubes are separated and will be retained with some 40 firmness in tube 2, while tube 1 is being replaced in position and screwed down to form a tight joint. In the preferred construction therefore, the lower end of the main magazine 16 rests rotatably upon the upper 45 surface of plug 25.

The magazine is retained in head 15 by transversely slotting the inner head portion 18, and the upper ends of the spacer blades and walls are inserted in these slots, as best 50 shown in Figs. 1 and 5. To retain the magazine in the upper tube 1, any suitable means may be provided, but preferably, in some cases, provision is made for its permanent retention, as follows: A shallow annular 55 channel 30 is formed in an upward portion of head member 18, and the upper end of tube 1 is pressed or rolled inward slightly to form a bead 31 located in the channel, tightly enough to prevent endwise displacement of the head and spacer, but loosely enough to permit rotation of the head in relation to tube 1.

Indicating means are desirably provided, which may consist simply of suitable index 65 characters 40 placed on the surface of head

portion 18 at points intermediate the spacer blades, or instead of definite characters, marking surfaces 41 may be provided as in Fig. 5. These marking surfaces may be simply cross-scored or roughened portions 70 of the head surface adapted to receive a pencil mark, as and for the purposes explained hereafter. The head 15 may be of any suitable material for this and other purposes. If made of suitable metals it 75 may be adapted by properly forming the roughened surfaces 41 to receive and retain pencil marks, or it may be made of celluloid or other plastic materials which can be easily provided in any suitable color or of 80 suitable composition or texture to permit proper marking for the purpose in view.

To co-operate with the index marks on head member 18, an aperture or window 45 is provided in tube 1, and this opening is 85 only large enough to expose one of the index marks, such as 40 or all or a part of one of the index surfaces 41.

Provision is desirably also made for carrying additional or spare leads, and this is conveniently done by forming longitudinal spaced channels 70 in the periphery of guide cylinder 4, and a spare lead such as 71 may be placed in each of the chambers or compartments thus formed. Access may be had to the spare leads when the casing members 1 and 2 are separated, by removing the plug 25, whereupon the upper ends of the chambers 70 are disclosed and any one or more of the spare leads may be removed or other 100 spare leads may be inserted in the chambers.

The compartments 20 of the main magazine are also loaded, or the leads may be changed, when the casing sections 1 and 2 are separated and plug 25 is removed, giving 105 access to the lower ends of the compartments 20.

The upper head portion 17 is desirably formed with a socket 50 to receive a rubber eraser 51, which may be detached and replaced in an obvious way. Desirably, the eraser is enclosed by a detachable cap 52, which is desirably formed of sheet metal and engages over the outer head portion 17 with a tight sliding fit, so that the magazine and selector 16 can be rotated by turning the cap.

The usual pocket clip 60 may be secured to casing portion 1.

Where index marks, such as 40, are placed on head portion 18 in the manufacture of the pencil, these marks may be made to agree with or to signify in some way the character or color of the lead to be placed in the corresponding compartment 20. Thus the character B most clearly seen in Fig. 1, may be intended to identify a blue lead or crayon 21 in a corresponding compartment 20. Similarly other letters may be employed, such as R, to designate a red lead in another compartment, 125 130

and so on. Otherwise numbers may be employed to designate the compartments, and the user may then attach an arbitrary significance to the numbers so that he will understand that a certain number or other character refers to a lead of a particular color or grade located in that compartment.

Otherwise when index or marking spaces or surfaces 41, Fig. 5, are provided, the pencil user may place a significant mark upon each of the index surfaces and this is most conveniently done by making a mark with the lead or crayon which is to be inserted in the corresponding compartment. Thus, if a 15 red crayon is to be inserted in the compartment, that crayon may be used to make a red check or other mark upon the corresponding surface 41, and so on, with respect to the other leads or crayons.

20 All of the leads in the main magazine except the lead in one particular compartment 20, are located by the spacers or blades 19, so that their lower ends rest on the solid upper surface of plug 25. One of the compartments, however, is located as shown in Fig. 3, so that the lead therein registers with aperture 26 in the plug, which in turn is in line with the guide hole or channel 5 in guide cylinder 4. The selector is turned by rotating cap 52 until a certain index mark appears at the aperture 45, indicating that the desired lead is positioned for movement through aperture 26 and passage 5. The pencil is then held point downward and 35 the lead falls through the guide channel and is directed into the bore of nipple 8. The screw tip 10 being loosened by unscrewing it, the lead passes between the separated grip fingers 9 until its point projects beyond the tip end, and the lead may then be positioned 40 so that the proper amount projects, according to the desires of the user, by holding the pencil tip slightly above a surface, such as a table surface, or by retaining the lead with a finger, and the lead is then securely 45 clamped in adjusted position by screwing up tip 10. A considerable range of movement of the clamp fingers is provided by the described arrangement, suitable for leads of 50 varying diameters, although it is usually desirable to use leads of a standard size, such as are readily available on the market, and therefore in most cases no great range of movement or adjustment of the grip fingers is necessary. Similarly the aperture in 55 the main portion of nipple 8 may be made to quite closely fit a lead of standard size and to provide an adequate lateral support for the portion of the lead within the pencil body, although this is not essential, and in 60 some cases considerable clearance may be provided to accommodate leads of considerably greater diameter, and such an arrangement is shown in the drawing.

65 As the lead is worn or broken in use, it

may be readjusted from time to time in an obvious way by manipulation of the screw tip 10. At any time when it is desired to use another lead, say for example, one of another color, the active lead is returned to 70 its magazine compartment by inverting the pencil and loosening the screw tip, whereupon the lead will drop back through passage 5 and aperture 26 into its compartment, which is usually ready to receive it, since, of course, 75 it is not necessary to reposition the active magazine while any lead is in position for use.

The active magazine or selector may then be repositioned to select another lead, which 80 may be adjusted and clamped for use in the manner previously described.

It is, of course, desirable to locate only one lead in each compartment of the active magazine, and while provision is here made for 85 only four active leads, obviously a greater number of compartments may be provided for a correspondingly greater number of leads, or a smaller number of compartments 90 may be provided, as may be desirable.

The structure is strong and durable and designed for economical production.

While not necessary in all cases, means 95 may be provided to aid in locating the selector magazine in any of its operative positions. For this purpose, as shown in Fig. 7, the cylindrical body 18 of the selector head may be provided near its upper end with a socket 18^a in which a spring 18^b is located to urge yieldingly outward a plunger 18^c having a rounded outer end. This end engages against the inward periphery of the shallow bead or flange 31 formed in the upper end of casing tube 1, and with shallow 100 rounded notches 31^a formed in the flange, the positions of these notches corresponding to different adjustable positions of the selector magazine 16. As cap 52 is turned, the plunger slips into the different shallow 105 notches 31^a and by the sense of feeling the 110 user can readily detect the correct location of the selector for the discharge of a lead from any one of the compartments through tube 5 to the tip. It is also desirable in some cases to provide means for completely closing the lower end of the selector magazine and to prevent the discharge of leads therefrom to the tip, or the return of a lead from the tip through passage 5 to the active magazine. For this purpose, as shown in Figs. 1, 5 and 6, a circular plate 80 is rotatably 115 located on top of the plug 25. The plate 80 has an aperture 81 which registers, when the plate is in one position, with the aperture 26 in plug 25. The plate has an arm or prong 82 extending through a segmental slot 83 in casing tube 1. An adjusting ring 84 is rotatably placed upon tube 1 and the end of prong 82 is inserted and clinched in the ring. 120 To close communication between the active 125 130

magazine and aperture 26 or passage 5, it is only necessary to turn ring 84 so that aperture 81 of plate 80 is out of registry with aperture 26, as shown in Fig. 6. It is then impossible for leads to pass to or from the active magazine and inadvertent discharge of a lead to passage 5 is thus prevented and similarly the inadvertent return of a lead to the wrong compartment of the magazine is also prevented. To reestablish communication and permit the movement of leads to and from the active magazine, it is only necessary to rotate ring 84 in the other direction, this movement being limited by contact of prong 82 with one end of slot 83. Aperture 81 is thus brought into registry with aperture 26 to permit the stated lead movements.

I claim:

1. A pencil comprising a tubular casing, a plug in the casing at a point intermediate its ends, a rotary magazine having a plurality of lead compartments and located in the casing above the plug, a member formed to provide a longitudinal, diagonal lead guiding channel in the casing below the plug, said member being provided with longitudinal chambers to hold spare leads, the plug being provided with an aperture aligned with said diagonal lead guide channel and arranged to permit movement of a lead to and from a magazine compartment selectively centered at said aperture, the plug also acting as a removable closure for the spare lead chambers, and a lead grip substantially at the tip of the casing and arranged to receive a lead from said lead guiding channel and adjustably clamp or release the lead.

2. A pencil comprising a tubular casing, a plug in the casing at a point intermediate its ends, a rotary magazine having a plurality of lead compartments and located in the casing above the plug, a member formed to provide a longitudinal diagonal lead guiding channel in the casing below the plug, said member being provided with spaced longitudinal chambers to receive spare leads, said chambers being arranged in peripheral portions of said member which are not occupied by the above mentioned lead passage, the plug being provided with an aperture aligned with said lead passage and arranged to permit movement of a lead to and from a magazine compartment substantially centered at said aperture and also serving as a removable closure for said spare lead chambers, and a lead grip substantially at the tip of the casing and arranged to receive a lead from said passage and adjustably clamp or release it.

3. A pencil comprising a two-part tubular casing, the parts having a connection approximately at the longitudinal center of the pencil, a magazine for active leads rotatively mounted in the upper casing section and

providing spaced pockets for a plurality of leads, a member located in the lower casing portion and having a longitudinal, inclined lead passage, and a removable spacing plug within the casing intermediate said member and the lower end of the magazine, said spacing plug having an aperture coinciding with said lead passage and a magazine pocket selectively positioned in relation to said aperture.

4. A pencil comprising a two-part tubular casing, the parts having a connection approximately at the longitudinal center of the pencil, a magazine for active leads rotatively mounted in the upper casing section and providing spaced pockets for a plurality of leads, a member located in the lower casing portion and having a longitudinal, inclined lead passage, and a removable spacing plug within the casing intermediate said member and the lower end of the magazine, said spacing plug having an aperture coinciding with said lead passage and a magazine pocket selectively positioned in relation to said aperture, the magazine pockets being accessible for removal or replacement of leads upon removal of said spacing plug.

5. A pencil comprising a two-part tubular casing, the parts having a connection approximately at the longitudinal center of the pencil, a magazine for active leads rotatively mounted in the upper casing section and providing spaced pockets for a plurality of leads, a member located in the lower casing portion and having a longitudinal, inclined lead passage, said member having spaced longitudinal compartments to receive spare leads, and a removable spacing plug within the casing intermediate said member and the lower end of the magazine, said spacing plug having an aperture coinciding with said lead passage and a magazine pocket selectively positioned in relation to said aperture.

6. A pencil comprising a two-part tubular casing, the parts having a connection approximately at the longitudinal center of the pencil, a magazine for active leads rotatively mounted in the upper casing section and providing spaced pockets for a plurality of leads, a member located in the lower casing portion and having a longitudinal, inclined lead passage, said member having spaced longitudinal compartments to receive spare leads, and a removable spacing plug within the casing intermediate said member and the lower end of the magazine, said spacing plug having an aperture coinciding with said lead passage and a magazine pocket selectively positioned in relation to said aperture, the spare lead pockets being accessible for removal and replacement of leads upon removal of said spacing plug.

7. A pencil comprising a casing, an active lead magazine having a plurality of com-
